UNITED STATES PATENT OFFICE

APPARATUS FOR DELIVERING SLIVERS INTO SLIVER CANS OR OTHER SIMILAR RECEPTACLES

Walter Sefton Suffern, Belfast, Ireland, assignor
to Fairbairn Lawson Combe Barbour Limited,
Leeds, England, a corporation of Great Britain

Application May 23, 1931, Serial No. 539,573
In Great Britain May 31, 1930

3 Claims. (Cl. 19—159)

This invention relates to apparatus for delivering slivers or ribbons of flax, hemp, jute, or other like fibres into sliver cans or other similar receptacles hereinafter called sliver cans. When a sliver can has been filled, or a predetermined quantity of sliver has been delivered to it, it is customary for the attendant to remove the full or partly filled can and replace it by an empty one.

According to this invention two sliver cans are used in conjunction with each delivery roller or pair of delivery rollers and means are provided for automatically changing the delivery of the sliver from one can to the other when one can has been filled, or when a predetermined length of sliver has been delivered to it without moving the cans for effecting such purpose. The aforesaid means may be combined with an indication device, such for example, as a bell mechanism, or with any other appropriate form of measuring motion.

In carrying out the invention a conductor or spout may be pivotally mounted on a stud suitably arranged in relation to the delivery rollers and be provided with an arm or lever which may be connected to the mechanism of a bell or other measuring motion which will at the correct instant rock the conductor or spout from its position over one sliver can to a corresponding position over the other sliver can thereby transferring the delivery of the sliver from one can to the other.

In the accompanying drawings:—

Fig. 1 is a front elevation, and

Fig. 2 a side elevation partly in section of a card drawing head showing the invention applied thereto.

Fig. 3 is an elevation and

Fig. 4 is a plan of the mechanism for moving the spout from one position to another.

Fig. 5 is an enlarged detail of a portion of the invention.

A, A¹ indicate the two sliver cans, B, B¹ the pair of delivery rollers, and C the conductor or spout. The latter is supported on an arm c of a two-armed lever that is pivotally mounted on a stud c¹ and is formed with an arm c² connected by a link c^{2x} carried in a bracket D. Fixed to the spindle c^{3x} is a bevel pinion c⁴ that gears with a bevel wheel c⁵ having 42 teeth with which is rigidly connected a star or ratchet wheel c⁶ having six teeth. Engaging with the latter is a pawl c⁷ pivoted on one arm c⁸ of a weighted lever c⁹ from which projects a lateral rib or ledge c¹⁰. c¹¹ indicates a bell wheel which revolves slowly

in the direction shown by the arrow and carries a projecting pin c¹². As this bell wheel revolves its pin c¹² passes under the rib or ledge c¹⁰ on the weighted lever c⁹ and lifts the latter so that the pawl c⁷ moves back behind one of the teeth on the wheel c⁶. After the lever has been lifted to enable the pawl c⁷ to drop behind the tooth the pin c¹² travels past the free end of the rib or ledge c¹⁰ thereby allowing the weighted lever c⁹ to fall and cause the pawl c⁷ to rotate the star wheel c⁶ through the space of one tooth, which is one sixth of a revolution, with the result that the bevel pinion c⁴ and crank arm c³ make half a revolution each time the bell wheel c¹¹ makes one complete revolution and allows the weighted lever c⁹ to drop back against the stop c¹³. By this arrangement each time the bell wheel c¹¹ completes a revolution and a can is filled with the sliver the condenser or spout is rocked at the correct instant from its position over one sliver can to a corresponding position over the other one and so transferring the delivery of the sliver from a full can to the other.

By reference to Fig. 5 the operating means of the two armed lever c is seen. The bevel wheel c⁴ is fixed on the pin c^{3x} and a crank arm c³ is fixed on the bottom of said pin. The crank arm c³ has a pin c^{4x} rigidly fixed in its free end. One end of the link c^{2x} is pivotally attached to the pin c⁴ and the other end of the link is pivotally connected to the free end c² of the double armed lever c. Inasmuch as the crank arm c³ is a great deal shorter than the link c^{2x}, it may make a complete revolution, (see Fig. 6) without bringing the end c² of the double armed lever into contact with the spindle D. As the link c^{2x} is attached to the underside of the free end of the crank arm c³ it passes beneath the lower end of the pin c^{3x} as the assembly rotates.

What I claim as my invention and desire to secure by Letters Patent in the United States is:—

1. In apparatus for delivering slivers into sliver cans wherein two sliver cans are used in conjunction with each delivery roller or pair of delivery rollers, the combination of a conductor or spout, a two-armed lever having one arm rigidly secured to the conductor or spout, a link pivoted at one end to the other arm of the two-armed lever, a rotatable shaft, a crank arm fixed to the lower end of said shaft and pivotally connected to the other end of the aforesaid link, a bevel pinion rigidly fixed on the upper end of the rotatable shaft, a bevel wheel gearing with said bevel pinion, a star wheel rigidly connected with said bevel wheel, a second two-armed lever

pivottally mounted in relation to said star wheel and carrying on one arm a pawl adapted to gear with the star wheel and on the other arm a weight and a laterally projecting rib or ledge, a slowly revolving wheel carrying a laterally projecting pin to engage the lateral rib or ledge on the weighted arm to actuate the latter to cause the pawl to rotate the star wheel through the space of one tooth and cause the bevel pinion 10 to make half a revolution each time the slowly rotating wheel makes one complete revolution and so rock the spout at the correct instant from its position over one sliver can to a corresponding position over the other one and so transfer 15 the delivery of the sliver from a full can to an empty one.

2. In an apparatus for delivering slivers into

sliver cans wherein two sliver cans are used in conjunction with delivery means, the combination of a conductor, a two-armed lever having one arm connected to said conductor, a link hinged at one end to the other arm of the lever, a rotatable shaft, a crank arm fixed to the lower end of said shaft and pivotally connected to the other end of said link, and means for operating said lever for changing the position of the conductor in relation to the delivery means whereby 10 the delivery of slivers to one can is switched to another can upon movement of the conductor. 5

3. The structure of claim 2, and means for timing the changing of position to result in the delivery of slivers to an empty can after one can 15 has been filled.

WALTER SEFTON SUFFERN.
